UNITED STATES PATENT OFFICE.

JOSEPH W. CUSHMAN, OF NEW YORK, N. Y., ASSIGNOR OF ONE-HALF TO
GEORGE F. WILCOXSON, OF SAME PLACE.

DESIGN FOR AN OIL-CAN.

SPECIFICATION forming part of Design No. 28,580, dated May 10, 1898.

Application filed September 29, 1897. Serial No. 653,526. Term of patent 14 years.

To all whom it may concern:

Be it known that I, JOSEPH W. CUSHMAN, a citizen of the United States, and a resident of the city, county, and State of New York, have 5 invented and produced a new and original Design for an Oil-Can, of which the following is a specification, reference being had to the accompanying drawings, forming part thereof.

Figure 1 is a side elevation showing my new 10 design; and Fig. 2, a section on the line 2 2 of Fig. 1, looking upwardly.

My design consists in an oil-can having the general shape and appearance represented in the accompanying drawings—that is to say, 15 the body A is oblong in cross-section, the angles or corners being rounded more or less to give a somewhat oval appearance. At one end the body slopes or tapers to the spout or outlet, the tapering shoulders a presenting a 20 very slightly concave appearance. At the end of the sloping shoulders and surrounding

the outlet is a circular flange B, turned downwardly and having its periphery milled or lined. Above this flange is a spout C, which is curved, as shown, and terminates in a pear-shaped or bulbous portion, the smaller end of which is toward the curved spout. 25

The essence of the design resides particularly in the body, oblong in cross-section, having the tapering or sloping shoulders and the 30 curved spout terminating in the bulbous or pear-shaped portion.

Having described my invention, what I claim as new, and desire to secure by Letters Patent, is—

The design for an oil-can as herein shown and described. 35

JOSEPH W. CUSHMAN.
